WETTING AGENT FOR MERCERIZING AND
A PROCESS FOR INCREASING THE WET-
TING POWER OF MERCERIZING LYESBurkhard von Becker, Aussig, Elbe, Germany, as-
signor to Sherka Chemical Co., Inc., a corpo-
ration of New YorkNo Drawing. Application December 13, 1940, Se-
rial No. 369,984. In Germany December 14,
1939

6 Claims. (Cl. 8—127)

This invention relates to a new and useful wetting agent and more particularly to a wetting agent for mercerizing purposes which is capable of increasing the wetting power of mercerizing lyes, and a method of using the same in mercerizing.

Mercerization has, among others, the purpose of imparting a silky luster to vegetable fibers, especially to cotton. In order to obtain this effect the textile fabric or yarn is treated in stretched condition with strong lyes, especially with a solution of sodium hydroxide (spec. weight: 1.24—1.33=28°—36° Bé.) and thereafter rinsed thoroughly. It is known to add to the lye, which without any addition wets the fabric or yarn only very slowly and irregularly, agents which are capable of considerably reducing the wetting time.

Such a wetting agent, in order to fulfill its purpose, must show the following properties:

- (a) A high wetting power,
- (b) Stability in a solution of sodium hydroxide (especially at 28—32° Bé.), and
- (c) Very little foaming.

I have found that the wetting power of mercerizing lyes can be essentially increased, by adding thereto isopropylated phenols, especially isopropyl phenol or isopropyl cresol, such as 1-methyl-3-isopropylphenol-(5), either alone or together with condensation products of amino-aryl sulfonic acids, aldehydes and phenols, such as are obtained, for instance, according to my copending application Serial No. 366,020 relating to "Sulfonic acids of high molecular weight and a method of making the same," filed November 16, 1940.

Among the isopropylated phenols that may be employed in carrying out the present invention are those obtainable as by-products in the manufacture of thymol.

Instead of the above mentioned condensation products, lower phenol homologues may also be used as solvent agents, capable of increasing solubility, especially when using more highly concentrated mercerisation lyes.

It has already been suggested to use mixtures of phenols or cresols and 2—12% hydrogenated phenols as wetting agents in mercerization. But in this known process the increase of wetting

power is caused by the addition of hydrogenated phenols only, while the phenol or cresol serves as an agent for facilitating solution of the hydrogenated phenols, which otherwise are insoluble in the mercerisation lyes, said phenol or cresol possessing practically no wetting power. In contrast hereto, the mercerisation lyes with the addition of isopropyl phenol or -cresol, show an excellent wetting effect, as is demonstrated by the following comparative test:

According to this invention, for instance, twisted yarn or a dense fabric of raw-cotton is completely wetted within two seconds in a solution of sodium hydroxide of 30° Bé., to which 15 0.7 vol. % of p-isopropylphenol is added, while, in contrast thereto, an addition of 1.4 vol. % of cresol or phenol itself does not show any wetting effect after 60 seconds.

The new additions distinguish themselves over the already known agents inasmuch as they combine in themselves the following properties:

High and constant wetting and shrinking effect, Stability even on standing in open air of the

mercerisation lye for a longer period of time, 25 If at all, very little foam formation, Clear solubility in the usual lye concentrations, No annoyance by offensive odors.

In contrast to the agents according to this invention the known additions show less advantageous effects, because one or several of the above mentioned properties are missing.

The following examples serve to illustrate the invention, without, however, limiting the same to them.

Example 1

A mercerisation lye of 30° Bé., to which 0.7 vol. % (0.55 weight %) of isopropyl phenol are added, wets dense raw-cotton fabric or twisted raw-yarn within two seconds. The wetting effect is not diminished even when the lye, composed according to this invention, is allowed to stand in the open air for several days at room-temperature.

Example 2

To a mercerisation lye of 28° Bé., there is added 1 vol. % (0.8 weight %) of a mixture of 45 67% of isothymol and 33% of the condensation product obtainable from butylphenol, sulfanilic

acid and formaldehyde. The clear solution shows the same unchanged wetting effect in the beginning as after standing for 2-3 weeks in an open vessel (1.5 seconds for dense cotton fabric or yarn). 5

Example 3

1.4 vol. % (1.1 weight %) of a mixture of 30% of isopropylphenol, 10% of isothymol and 60% of a condensation product of sulfanilic acid, cresol (German Pharmacopoeia, 6th edition) and formaldehyde, dissolved in a solution of sodium hydroxide of 32° Bé., cause excellent and constant wetting and shrinking effect (1.5-2 seconds). 10

The volume of the foam consisting of large bubbles which is obtained on strongly shaking the mixture for 10 seconds amounts to about 70-80% of the used volume of the liquid; after 1½ minutes to foam is decreased to about 3-5% of the volume of the liquid. 15

Such a wetting agent may also contain other additions, such as, for instance, ethereal oils, i. e., terpineol, aromatic hydrocarbons, i. e., xylene, or alcohols, i. e., methanol, and others. 20

Example 4

1.0 weight % of a mixture of 70% of isothymol and 30% of cresol (German Pharmacopoeia, 6th edition), dissolved in a solution of sodium hydroxide of 28° Bé., shows excellent wetting effects similar to those shown by the preceding preparations and only little foam formation. 25

Example 5

A mercerizing wetting agent with the same properties as those of Example 4 has the following composition: 30

	Grs.
Isopropylphenol	66.0
Cresol (German Pharmacopoeia, 4th edition)	34.0

The following table indicates the time in seconds, which is necessary for causing complete wetting with the wetting agents according to this invention, whereby mixtures of alkylated phenols with cresol (German Pharmacopoeia, 4th edition) 35

are used as wetting agent and solutions of sodium hydroxide of 28° Bé. as mercerisation lye. 40

Alkylated phenol	Proportion of alkylated phenol: cresol	Wetting time in seconds	Addition in per cent calcul. to lye
Isopropyl phenol	2:1	2.0	1.4
Isopropyl phenol dist.	2:1	3.0	1.4
Isopropyl phenol	4:1	2.0	1.4
Do		2.0	0.7
Without cresol			
Isopropyl cresol	2:1	2.5	1.4
Isopropyl p-cresol	2:1	2.0	1.4
Isothymol	2:1	1.5	1.4
Thymol	2:1	About 60	1.4
Cresol		About 60	1.4

What I claim is:

1. A mercerizing wetting agent, comprising an isopropylated phenol and a condensation product of an aminoarylsulfonic acid, an aldehyde and a phenol. 20
2. A mercerizing wetting agent, comprising an isopropylated phenol, a condensation product of an aminoarylsulfonic acid, an aldehyde and a phenol, and a member of the group consisting of phenol and cresol. 25

3. A process for improving vegetable textile fibers, comprising treating said fibers with a mercerizing lye of caustic alkali containing an isopropylated phenol, and a condensation product of an aminoarylsulfonic acid, an aldehyde and a phenol. 30

4. A process for improving vegetable textile fibers, comprising treating said fibers with a mercerizing lye of caustic alkali containing isothymol and a condensation product of an aminoarylsulfonic acid, an aldehyde and a phenol. 35

5. A mercerizing wetting agent comprising a mixture of isothymol and the condensation product of an amino-aryl-sulfonic acid, an aldehyde and a phenol. 40

6. A mercerizing wetting agent comprising a mixture of isothymol, a member of the group consisting of phenol and cresol, and a condensation product of an amino-aryl-sulfonic acid, an aldehyde and a phenol. 45

BURKHARD v. BECKER.
